CLAIM

The ornamental design for a pickleball paddle, as shown and described.

DESCRIPTION

FIG. 1 is a perspective view of a pickleball paddle in accordance with my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines shown are included for the purpose of illustrating portions of the pickleball paddle which form no part of the claimed design.

The SPARTUS "S" logo forming part of the claimed design is a trademark of Spartus LLC.

1 Claim, 5 Drawing Sheets
